UNITED STATES PATENT OFFICE

110,550

DESIGN FOR A VENDING MACHINE

Abraham E. Sandhaus, Kansas City, Mo.

Application April 27, 1938, Serial No. 76,762

Term of patent 7 years

To all whom it may concern:

Be it known that I, Abraham E. Sandhaus, a citizen of the United States, residing at Kansas City, in the county of Jackson and State of Missouri, have invented a new, original, and ornamental Design for a Vending Machine, of which the following is a specification, reference being had to the accompanying drawing, forming a part thereof.

Figure 1 is a front elevation of a vending machine showing my new design.

Fig. 2 is a side elevation of the same, and
Fig. 3 is a plan view of said design.

I claim:

The ornamental design for a vending machine,
as shown.

ABRAHAM E. SANDHAUS.
